(57) **CLAIM**

The ornamental design for a jump starter with inflator, as shown and described.

DESCRIPTION

FIG. 1 is a front, left and bottom perspective view of a jump starter with inflator design showing my new design.

FIG. 2 is a rear, right and bottom perspective view of a jump starter with inflator.

FIG. 3 is a front view of a jump starter with inflator.

FIG. 4 is a rear view of a jump starter with inflator.

FIG. 5 is a left side view of a jump starter with inflator.

FIG. 6 is a right side view of a jump starter with inflator.

FIG. 7 is a top view of a jump starter with inflator; and,

FIG. 8 is a bottom view of a jump starter with inflator.

The broken lines in the drawings depict portions of the jump starter with inflator that form no part of the claimed design.
